TIRE DISPLAY RACK

Robert C. Shape, 1309 Niles Road SE, Warren, Ohio

Filed Feb. 27, 1963, Ser. No. 73,759

Term of patent 14 years

(Cl. D80—9)

FIGURE 1 is a front perspective view taken from one side of a tire display rack showing my new design, the rear being substantially the same as the front shown; and

FIGURE 2 is an elevational view taken from the side shown in FIGURE 1, the opposite side being a mirror image thereof.

The broken line representative of advertising matter in FIGURE 1 is for the purposes of illustration only.

I claim:

The ornamental design for a tire display rack, substantially as shown and described.
